COTTON GIN OF THE SAW TYPE.
APPLICATION FILED APR. 12, 1916.

Patented Oct. 24, 1916.

3 SHEETS—SHEET 3.

UNITED STATES PATENT OFFICE.

LELAND L. FOSS AND CHRISTIAN C. FOSS, OF VIDALIA, GEORGIA.

COTTON-GIN OF THE SAW TYPE.

1,202,699.

Specification of Letters Patent.

Patented Oct. 24, 1916.

Application filed April 12, 1916. Serial No. 90,753.

To all whom it may concern:

Be it known that we, LELAND L. Foss and CHRISTIAN C. Foss, citizens of the United States, residing at Vidalia, in the county of Toombs, State of Georgia, have invented certain new and useful Improvements in Cotton-Gins of the Saw Type; and we do hereby declare the following to be a full, clear, and exact description of the invention, 10 such as will enable others skilled in the art to which it appertains to make and use the same.

This invention relates to a cleaning and feeding device for gins of the saw type.

15 The primary object of the invention resides in the provision of means for separating the cotton from the stones or other foreign material before the cotton is fed to the saws.

20 A further object of the invention resides in so constructing the separating means that the cotton will not be retarded in its movement to the saws.

25 A still further object of the invention resides in the provision of novel actuating means for the separating means so that the speed of the latter may be varied in proportion to the speed of the picker roller.

With these and other objects in view, such 30 as will appear as our description progresses, our invention comprises the combination and arrangement of parts as set forth in and falling within the scope of the appended claims.

35 In the drawing: Figure 1 is a sectional view of a saw gin with our invention incorporated therein; Fig. 2 is a side elevation; Fig. 3 is a front elevation; Fig. 4 is a detail showing the driving means for the fan; 40 Fig. 5 is a fragmental perspective view of the cotton deflector; Fig. 6 is a side elevation of the gin with a modified form of driving means incorporated therein; Fig. 7 is a fragmental sectional view on line 7—7 45 of Fig. 6; Fig. 8 is a vertical sectional view of a modified form of blower, and Fig. 9 is a similar view taken at right angles to Fig. 8.

In the drawing we have illustrated a cotton gin of the saw type similar to the gin 50 described in the co-pending application filed January 29, 1916, Serial No. 75,064. Inasmuch as this is true it is not deemed necessary or advisable to enter into a detailed description of the structure of the gin and we 55 will therefore describe only the improve-

ments, referring to the gin as it becomes necessary. Mounted on the frame 1 of the gin is a hopper 2 in which a picker roller 3 is mounted on a shaft 4. Cotton and foreign material are fed to the picker roller by the feed rollers 5 which are located above the picker roller.

In order that the cotton may be separated from foreign material and conveyed to the saw breast 6, we have provided a deflector which includes a pair of end pieces 7 having hooks 8 and 9 thereon and extending between these end pieces is a curved plate 10 which forms the cover of the deflector, 70 the lower portion of the deflector being entirely open. Extending between the end pieces 7 and between the plate 10 and the lower edges of the end pieces is a guide plate 11 on which an auxiliary plate 12 is adjustably mounted, the plate 12 being held on the guide plate 11 by setscrews 13 which pass through slots in the plates. The deflector is supported by the engagement of the hooks 8 and 9 with pins 14 on the hopper 2 and pins 15 which are carried by braces 16. The lower open end of this deflector is directed toward the upper open end of the saw breast 6. It will thus be seen that the deflector may be readily removed and replaced when desired.

Mounted beneath the picker roller 3 is a fan casing 17 which extends throughout the entire length of the machine and is provided with a nozzle 18 having its opening 19 directed toward the deflector above the edge of the plate 12. A fan 20 is mounted in this casing 17 and extends throughout the length of the same so that a blast of air is directed from the opening 19 immediately 90 beneath the lower edge of the cotton board 21 and above the upper edge of the plate 12. It will thus be seen that as the cotton is fed from the board 21 the blast from the opening 19 will strike the same and blow the cotton 95 against the plate 10 from whence it will be fed by the assistance of the guide plate 11 to the breast 6. It is to be noted that the nozzle 18 is so directed that the movement 100 of the cotton from the board 21 will be enhanced rather than retarded. The blast of air will not be sufficient to raise the stones and other heavy foreign material so that the stones will drop from the edge of the cotton board 21 and will therefore not pass to the 110 breast 6.

In order that the feed rollers 5, the picker

roller 3 and the fan may be rotated in a certain definite ratio, I have secured a pulley 22 to the shaft 4, which pulley is actuated by a belt 23 passing over a pulley 24, which latter pulley is actuated by a belt 25 which passes to the power shaft. A friction disk 26 is secured to the end of the shaft 4 remote from the pulley 22 and a similar disk 27 is mounted on a stub shaft above the disk 26. Extending vertically and across the faces of the disks 26 and 27 is a shaft 28 on which a friction wheel 29 is secured, which wheel is adapted to contact with the face of the disk 26. This shaft is further provided with a friction wheel 30 which is slidable on the shaft but rotatable therewith and which is adapted to contact with the friction disk 27. This shaft 28 is mounted in bearings carried by levers 31 which are hinged, at 32, and are provided with screws 33. These screws act so that the friction wheels 29 and 30 may be drawn tightly into contact with or released from the disks 26 and 27 as will be readily understood. Now this shaft is slidable vertically in its bearings and its movement is controlled by a lever 34 which is operable on a rack 35 and is attached to the upper end of the shaft. The friction wheel 30 is adjusted vertically on the shaft by means of a shipper lever 36 which is operable on a rack 37. Secured to the stub shaft on which the disk 27 is mounted is a pinion 38 which meshes with a gear 39 carried by one of the feed rollers 35 at one of its ends. The ends of the feed rollers remote from the last mentioned end are provided with intermeshing gears 40. Thus it will be seen that when the pulley 22 is actuated together with the disk 26 that the feed rollers will be actuated together with the picker roller 3. It will be further seen that by adjusting the friction wheel 30 to and away from the center of the disk 27 the speed of the feed rollers will be varied. In order that the fan 20 may be driven, I have provided one form of mechanism which is disclosed in Fig. 4 and which includes a gear 41 formed on the pulley 22 which meshes with a pinion 42 on the fan shaft. I have however provided a disk 43 which is secured to the fan shaft and with which a friction wheel 44, which is secured to the shaft 28, coöperates. It will be seen with this latter arrangement that when the lever 34 is actuated to move the shaft 28 upwardly, for instance, the friction wheel 29 will be moved away from the center of the disk 26 and the friction wheel 44 will be moved toward the center of the disk 43 so that the speed of the fan will be increased. Of course the reverse will be true when the lever is moved in the opposite direction. The stub shaft on which the disk 27 is mounted is indicated by the reference character 45 in Fig. 7 of the drawing and this

shaft is slidable in a bearing 46, its movement being effected by a lever 47. The object of the sliding movement of this stub shaft is to permit the frictional engagement between the friction wheel 30 and the disk 27 to be varied independently of the variation by the lever 31.

Referring particularly to Figs. 8 and 9 of the drawing it will be seen that I have produced a modified form of fan casing and this form includes an elongated casing 48 which extends from end to end of the machine and the bottom 49 of which inclines upwardly toward the top. Extending from this casing 48 is a nozzle 50 which projects from end to end of the machine and is directed toward the deflector for the cotton. This casing 48 is not constructed to receive the fan but only to convey the air to the deflector from a fan located externally of the machine, which air is conveyed to the casing by any suitable conveyer 51, in which conveyer a plate or damper 52 is mounted, which may control the velocity of the air leaving the nozzle 50.

While we have illustrated and described a particular embodiment of our invention, it has merely been for the sake of convenience and we do not wish to be limited to that particular embodiment as it is obvious that numerous changes may be made in the details of construction without departing from the spirit of the invention or exceeding the scope of the appended claims.

What we claim is:—

1. In a saw cotton gin, the combination with a picker roller, of a cotton board extending therefrom, a breast, a deflector arranged between the cotton board and breast and above the former and means for blowing the cotton in its passage from the cotton board to the breast to free the same from relatively heavier foreign material, the said means being so arranged as to assist the cotton in its passage from the cotton board.

2. In a saw cotton gin, the combination with a plurality of saws and a breast therefor, of a picker roller, a cotton board extending from the roller, a deflector including an upper plate and an adjustable guide plate mounted between the cotton board and the breast and above the former and a fan located beneath the cotton board to blow the cotton as it passes from the end of the cotton board and to deliver it between the upper plate and the guide plate of the deflector, free from relatively heavier foreign material.

3. In a saw cotton gin, the combination with a picker roller, of a cotton board extending therefrom, a breast, a deflector including an upper plate and an adjustable guide plate mounted between the cotton board and breast, the guide plate being adjustable to vary the distance between the cot-

- ton board and its edge and means for directing a blast of air to the space between the guide plate and cotton board and against the upper plate of the deflector.
5. 4. In a saw cotton gin, the combination with a picker roller and a breast, of a cotton board extending from the picker roller, a deflector mounted between the picker roller and breast and including an upper plate and 55 a spaced guide plate and means operating on the cotton in the general direction of its movement from the cotton board to move it to the space between the upper plate and guide plate of the deflector.
10. 5. In a saw cotton gin, the combination with a picker roller and a breast, of a cotton board extending from the picker roller in the direction of the breast and means active on the cotton in the direction of its movement from the cotton board to free the cotton of relatively heavier foreign material. 60
15. 6. In a cotton cleaning machine, the combination with a picker roller and feed rollers, of a fan for directing the blast of air into the line of movement of the cotton as it passes from the picker roller, means for driving the feed rollers, means for driving the fan and means for varying the relative speeds of the feed rollers and fan. 65
20. 7. In a cotton cleaning machine, the combination with feed rollers for the cotton, of a fan arranged below the feed rollers and adapted to blow the cotton in its passage from the same, means for varying the speed 70 of the fan and independent means for varying the speed of the feed rollers.
25. 8. In a cotton cleaning machine, the combination with feed rollers for the cotton, of an air blast producing mechanism, means for directing the air blast into the line of movement of the cotton from the feed rollers and in a direction away from the latter, means for driving the feed rollers, means for driving the blast producing mechanism and means for varying the relative 75 speeds of the said rollers and mechanism.
30. 9. In a saw cotton gin, the combination with a picker roller, of a cotton board extending therefrom, a breast, a guide for the 80 cotton disposed between the cotton board and breast, a fan casing located beneath the picker roller and having a nozzle directed toward the guide and away from the lower edge of the cotton board, a fan located in the casing, a friction disk mounted on one end of the picker roller shaft, a similar disk mounted on the adjacent end of the fan shaft, a shaft vertically slidable across the faces of the disk and friction wheels mounted on the shaft and contacting with the faces 85 of the wheels on opposite sides of their centers.
35. 10. In a saw cotton gin, the combination with a picker roller, of a fan for blowing the cotton in its passage from the picker 90 roller and means for varying the speed of the fan, the said means including friction disks secured to the ends of the picker roller shaft and fan shaft, a vertically slidable shaft, friction wheels secured to the last mentioned shaft and contacting with the faces of the wheels on opposite sides of their centers, means for increasing the pressure of the wheels on the disks and means for varying the positions of the wheels with relation to the centers of the disks.
40. 11. In a saw cotton gin, the combination with a picker roller and a breast, of a casing for directing a blast of air between the picker roller and breast to blow the cotton 95 in its passage from the former to the latter and means for regulating the velocity of the air passing from said casing.
45. 12. In a saw cotton gin, the combination with a picker roller and a breast, of feed 100 rollers, a fan for blowing the cotton in its passage from the picker roller to the breast, means for varying the speed of the fan and independent means for varying the speed of the feed rollers.

In testimony whereof, we affix our signatures, in the presence of witnesses.
